UNITED STATES PATENT OFFICE.

ALEXANDER CHURCHWARD, OF NEW YORK, N. Y., ASSIGNOR TO GENERAL ELECTRIC COMPANY, A CORPORATION OF NEW YORK.

LOCKING DEVICE FOR AUTOMOBILES.

No. 812,726.

Specification of Letters Patent.

Patented Feb. 13, 1906.

Application filed June 30, 1904. Serial No. 214,713.

To all whom it may concern:

Be it known that I, ALEXANDER CHURCHWARD, a citizen of the United States, residing at New York city, county of New York, State of New York, have invented certain new and useful Improvements in Locking Devices for Automobiles, of which the following is a specification.

My invention relates to power-transmission mechanisms for automobiles, and refers particularly to transmission mechanisms employing dynamo-electric machines performing the function of clutches with variable slip. Several transmission mechanisms have been devised in which a dynamo-electric machine is employed to transmit the whole or a portion of the torque. Such a dynamo-electric machine forms what may be called a "variable-speed magnetic clutch"—that is, a magnetic clutch having a variable slip between its two members. This slip generates a current in the machine which may be utilized to assist in driving the load by supplying it to a second dynamo-electric machine connected mechanically to the load, and the speed and torque of the vehicle may be conveniently regulated by controlling the circuits of the machines. Where the transmission of the engine torque to the driving-wheels depends upon a dynamo-electric machine, a breakdown of the windings or of the source of current therefor makes it impossible to deliver any power from the engine to the driving-wheels. Such an action consequently renders the automobile completely helpless, which is a great inconvenience if the breakdown occurs at some distance from the nearest repair-shop.

The object of my invention is to prevent a complete disabling of a transmission mechanism of the type described above; and it consists in providing means for mechanically locking the two members of the machine together in case of an emergency. By this means the operator is enabled to take the vehicle home under its own power.

My invention will best be understood from the accompanying drawings, in which—

Figure 1 shows an automobile power-transmission mechanism provided with a locking device in accordance with my invention. Fig. 2 shows diagrammatically the connections of the several parts of the mechanism,

and Fig. 3 shows an enlarged view of the dynamo-electric machine to which the locking mechanism is applied.

In the drawings I have shown my invention as applied to a power-transmission mechanism of the type described in Patent No. 723,168, issued to H. Lemp March 17, 1903.

In the drawings, E represents a prime mover, such as a gas-engine, carrying on its shaft the armature of the dynamo-electric machine M. The shaft of engine E is connected by the sprocket-chain S to one member D of the differential gear. A second member D' is connected by sprocket-chain S' to the armature of a second dynamo-electric machine G. The third member D² of the differential gear is connected to the driving-wheel. With this arrangement it will be seen that if the circuit of the dynamo-electric machine G is open and the engine is started the driving-wheel W will remain stationary and the generator G will be driven through the differential gear by the engine E. Now if the circuit of the generator G is closed a current will be produced which will cause a torque to be exerted between the armature and field of the machine. In place of wasting in resistances the energy produced by generator G it may be delivered to the motor M on the engine-shaft, which acts to add its torque to that of the engine. By varying the field strength of generator G the amount of current, and consequently the torque, may be varied, thereby varying the speed and torque of the driving-wheel W. As the field strength of generator G is increased the speed of the armature relative thereto is decreased. When the generator has its full field strength, the machine may be short-circuited and will act as a magnetic clutch, the armature slipping the small amount necessary to generate the current for producing the required torque. The machine may again be reintroduced into circuit with its field reversed, and it will then act as a motor to drive member D' of the differential gear in the opposite direction, the motor M acting as a generator and absorbing a portion of the engine torque to deliver to the machine G. In this manner the speed of the vehicle is further increased, but with a reduced torque. One set of connections for accomplishing the above results are shown in Fig. 2, in which the generator G is shown with

a separately-excited field controlled by the rheostatic reversing-switch R. The machine M is shown as a shunt-motor.

The arrangement as thus far described is 5 completely disclosed in Patent No. 723,168, above referred to, and has been described here merely for the purpose of giving a clear understanding of my invention.

It is obvious that if the generator G should 10 become disabled no magnetic torque could be produced between the field and armature, and consequently no torque could be delivered to member D' of the differential gear. This means that the transmission mechanism 15 would be disabled, since the generator G would consequently run freely without delivering any torque to the driving-wheel. In case of such an emergency I provide the locking device L, which, as shown in Fig. 3, consists of a bolt extending through the field-frame or bearing and entering the armature body or spider. The two parts are thus 20 locked together and member D' of the differential gear held stationary. The engine 25 torque may then be delivered directly to the driving-wheel W, and although variation of the speed and torque cannot be obtained without controlling the engine speed it is possible to run the vehicle under its own 30 power and in that manner to reach a place where repairs can be made.

My invention is not limited to the particular form of transmission mechanism shown, but is applicable to any transmission mechanism 35 comprising a dynamo-electric machine arranged to act as a slipping clutch and to supplying the current generated thereby to a second dynamo-electric machine for the purpose of varying the load.

What I claim as new, and desire to secure 40 by Letters Patent of the United States, is—

1. In an automobile, speed-changing power-transmitting mechanism comprising two dynamo-electric machines electrically and mechanically connected, and means for locking 45 the field and armature of one of said machines together.

2. In an automobile, speed-changing power-transmitting mechanism comprising two mechanically-connected dynamo-electric machines, one of said machines being arranged to act as a slipping clutch and to supply current generated by said slipping to the second machine, and means for locking the field and armature of the first machine together. 55

3. In an automobile, a prime mover, a differential gear having one member connected to said prime mover and a second to the load, a dynamo-electric machine connected to the third member of said gear, and means for 60 locking the field and armature of said machine together.

4. In an automobile, a prime mover, a differential gear having one member connected to said prime mover and a second member to 65 the load, a dynamo-electric machine connected to one of said members, a second dynamo-electric machine connected to the third member of said gear, and means for locking the field and armature of the latter machine 70 together.

In witness whereof I have hereunto set my hand this 29th day of June, 1904.

ALEXANDER CHURCHWARD,
